CROSSHEAD

Robert E. Freund, Phillips, Tex., assignor to
 Phillips Petroleum Company, a corporation of
 Delaware

Application January 22, 1945, Serial No. 574,015

10 Claims. (Cl. 103—1)

1

This invention relates to crossheads. In one of its more specific aspects it relates to a pump crosshead carrying a plunger in which the plunger is removable without disturbing the alignment of the crosshead bearings, or causing the bearing surfaces of the bearing shoe on the crosshead and on the slide therefor to touch any surface not touched in normal operation of the pump during the pumping stroke. In another specific aspect it relates to a crosshead assembly in a duplex plunger pump which allows removal of the plungers without breaking down the crosshead assembly.

Much difficulty has been experienced in prior art in repairing pumps because the removal of the plungers is impossible without disaligning the crosshead or crosshead assembly. In moving the crosshead out of its usual pumping position, it is easy for an unskilled worker to scar the bearings with resulting wear. The reassembly of the crosshead in proper position requires the skill of a millwright. Even a skilled worker finds the reassembly and adjustment of the crossheads to be a time consuming operation.

The present invention avoids moving the crossheads from their bearing surfaces and reduces the number of operations necessary to take out a plunger. In relation to a 3" x 10" Worthington duplex plunger pump, as an example, the saving in time amounts to five man-hours per plunger which is more than 65% of the time needed.

One object of the present invention is to facilitate the repair of a pump.

Another object is to avoid scarring the bearing surfaces, to save time, to allow the employment of unskilled workers, and to avoid having to align the crossheads after replacing a plunger.

Another object is to make the plunger readily removable through the crosshead.

A further object is to provide a novel and useful construction of parts of a pump as shown, described, and claimed.

Numerous other objects and advantages will be apparent to those skilled in the art upon reading the accompanying specification and looking at the accompanying drawing.

In the drawing:

Figure 1 is a cross-sectional elevation taken through a plunger pump crosshead embodying the present invention, taken along the line 1—1 of Figure 2.

Figure 2 is an elevational view with parts in cross section of the crosshead and plunger assembly of Figure 1.

2

Figure 3 is an elevational view of the cover plate used in the structure of Figure 1.

Figure 4 is a plan view with parts broken away of a crosshead and plunger assembly for a duplex plunger pump embodying same crosshead construction as shown in Figures 1 to 3 inclusive.

In Figure 1 a pump frame 6 may be provided with a bushing 7 which is generally made of brass or bronze for guiding a crosshead operating means which may comprise a driving rod 8. Mounted on frame 6 is a pump cylinder 9 in which it is customary to reciprocate a pump plunger 11.

While a pump plunger 11 is shown, it is obvious that a piston could be employed instead of plunger 11 and that this piston could have piston rings sealing to cylinder 9 without changing the principle of the present invention and, therefore, the word "plunger" as used in the claims is intended to cover all usual types of pistons and plungers.

When the invention is applied to a plunger type pump, as shown, it is customary to have a stuffing box 12 with the usual gland 13 sealing between the plunger 11 and the cylinder 9.

25 In order to align and guide the plunger 11 it is customary to provide a crosshead. In the present invention this crosshead 14 is provided with a bearing shoe 16 having a bearing surface 17 which slides in reciprocation on slide 18, as shown in Figure 2.

Crosshead 14 is connected to crosshead operating rod 8 by means of crosshead end plate 19, studs 21, nuts 22, screw thread 23 on the end of rod 8 and lock nut 24.

30 In order to carry out the objects of the present invention, crosshead 14 is provided with a hole 26 which hole has the same axis as the axis of plunger 11. Hole 26 has a diameter greater than any diameter of plunger 11 so that plunger 11 may pass through hole 26 without any difficult manipulation.

A cover plate 27 is provided having a boss 28. The boss has a sliding fit in hole 26 and cover plate 27 is provided with a recess 29 on its surface for the reception of the butt end 31 of plunger 11.

As shown in Figure 3, recess 29 and butt end 31 which has a sliding fit therein are both smaller than boss 28 which has a sliding fit in hole 26.

Easily disengageable means is provided for holding parts 14, 27 and 11 in assembled relation as shown in Figure 1, and this disengageable means may consist of studs 32, nuts 33, and retaining ring 34. However, many other forms of disengageable clamping means exist in the prior art and any of these old disengageable means, or

similarly devised disengageable means, may be employed to hold parts 14, 27, and 11 assembled without departing from the present invention.

While not essential in all pumps, it is common practice to cool the plunger internally with a cooling fluid such as water and, therefore, in Figure 1 a means has been invented to allow for such cooling.

The cooling fluid enters through an inlet pipe 35 which is brought around to connect to an inlet passage 36 formed in plate 27. The manner in which the inlet pipe 35 is supplied with fluid is not part of the present invention but the end of inlet pipe 35 is commonly either connected to a flexible rubber tubing which allows for movement of the crosshead, or pipe 35 may have its end telescopically arranged in a stationary pipe, in which case a usual stuffing box may be employed. (These arrangements are not shown.)

Plunger 11 contains an axial hollow cavity 37. Plate 27 is provided with an outlet passage 38 into which a fluid distributing pipe 39 may be screwed or otherwise fastened for the purpose of forcing the cooling fluid to circulate down to the far end 41 of plunger 11. The disposal of the cooling fluid after leaving outlet 38 is immaterial to the invention but may be done by means of pipe 42 which may be of similar construction as that described in relation to pipe 35. The discharge cooling fluid may be thrown away or may be cooled and recirculated in a manner well-known to the art.

In Figure 2 side rods 43 are shown in cross section but it should be understood that when only one crosshead 14 is employed that side rods 43 may, in some instances, be dispensed with as unnecessary.

In Figure 4 is shown a crosshead assembly generally designated as 44. This crosshead assembly is for a duplex plunger pump in which the two plungers 11, 11 are oppositely disposed and fit into oppositely directed cylinders, which cylinders are not shown. The advantage of this construction is to give a double action in that while one plunger 11 is advancing and doing work the other plunger is being withdrawn, and on pulling the crosshead assembly 44 in the other direction the other plunger will then do the work.

In Figure 4 the two crossheads 14, 14 are connected together by side rods 43 and are held to the side rods by means of shoulders on the side rods and nuts 15. The other parts being similarly numbered and similar to those in Figure 1 will not be discussed further.

Operation

The operation of the pump is similar to all other plunger pumps during the pumping cycle. Shoe 16 travels back and forth on bearing surface 18 in normal pumping operation from one extreme position to another extreme position and the distance between these extreme positions is of limited extent and is a distance shorter than the length of plunger 11.

In order to remove plunger 11 without moving surface 17 away from any position on bearing 18 beyond the two extreme positions it takes in normal pumping operation, the following sequence of operations may be employed.

Nuts 22 are unscrewed from studs 21 and plate 49 is pushed toward the left-hand side of the drawing. Nuts 33 and studs 32 are removed and plunger 11 and ring 34 are pushed to the right side of the drawing as far as possible. If tube 39 is present it may be easily unscrewed with a

wrench inserted between the butt end 31 and plate 27. When tube 39 is unscrewed it is moved to the right side of the drawing inside plunger 11 as far as possible.

Crosshead 14 is then carefully moved to its extreme pumping position, care being taken not to move it past the place that it has worn for itself in bearing surface 18 during normal pumping operation.

Pipes 35 and 42 are disconnected from plate 27 and end plate 27 is moved to the right until boss 28 has come out of hole 26. Plate 27 is then lifted upwardly and removed.

Crosshead 14 is then carefully moved on its shoe 16 along the bearing surface 18 to the extreme right-hand position that the crosshead takes in normal pumping operation as can easily be seen by the place it has worn for itself in surface 18. Plunger 11 is then removed to the left through hole 26 in crosshead 14 and upwardly out of the structure shown in Figure 1.

Plunger 11 and stuffing box 12 may then be removed without having disturbed the alignment of the crosshead 14.

The installation of a new plunger or the return of plunger 11 obviously proceeds in an opposite manner from the above steps of disassembly and, therefore, it is not regarded as necessary to describe such further operations.

In Figure 4 where there are two crossheads 14, 14 connected by side rods 43 and nuts 15, the operations are performed first on one plunger 11 and then on the other plunger 11 and at no time is it necessary to spoil the alignment of crossheads 14, 14 and side rods 43 nor to otherwise disassemble the crosshead assembly 44.

It is obvious that I have provided apparatus for carrying out the above mentioned objects of the invention and other objects and having the above mentioned and inherent advantages, and it is believed obvious that various changes in shape, construction, and proportion of parts may be made without departing from the scope of the present invention, which scope is defined and set forth only in the following claims.

Having described my invention, I claim:

1. In a duplex plunger pump having a plurality of cylinders; a crosshead assembly comprising a first crosshead, a second crosshead, and side members securing said crossheads together; a plunger operated by each said crosshead in co-operative relationship with one of said cylinders; and means for reciprocating said crosshead assembly in pumping; the improvement in which each said crosshead has a hole of a diameter larger than any cross section of the plunger operated thereby, a plate disposed in a position to cover said hole, and disengageable means securing said plate to said crosshead in said position and securing the plunger operated by said crosshead against said plate and to said crosshead, whereby said disengageable means may be disengaged to allow removal of said plate and withdrawal of said plunger through said hole thereby avoiding disassembly of said crosshead assembly when removing a plunger.

2. The improvement of claim 1 in which the plunger is hollow and fluid cooled internally, said plate having an inlet passage and an outlet passage for the cooling fluid, means to supply cooling fluid to said inlet passage, said inlet and outlet passages communicating with the hollow interior of said plunger, and a fluid distributing tube detachably secured to said cover plate and forming a continuation of one of said passages

whereby circulation of said fluid inside said plunger is improved at the end of said plunger farthest from said cover plate.

3. The improvement of claim 1 in which the plunger is hollow and fluid cooled internally, said plate having an inlet passage and an outlet passage for the cooling fluid and means to supply cooling fluid to said inlet passage, said inlet and outlet passages communicating with the hollow interior of said plunger.

4. In a plunger pump having a cylinder; a cross-head, a plunger operated by said crosshead in cooperative relationship with said cylinder; and means for reciprocating said crosshead in pumping; the improvement in which said crosshead has a hole of a diameter larger than any cross section of the plunger operated thereby, a plate disposed in a position to cover said hole, and disengageable means securing said plate to said crosshead in said position and securing the plunger operated by said crosshead against said plate and to said crosshead, whereby said disengageable means may be disengaged to allow removal of said plate and withdrawal of said plunger through said hole thereby avoiding movement of said crosshead beyond the normal extreme positions of said crosshead due to said reciprocation in pumping.

5. The improvement of claim 4 in which the plunger is hollow and fluid cooled internally, said plate having an inlet passage and an outlet passage for the cooling fluid, means to supply cooling fluid to said inlet passage, said inlet and outlet passages communicating with the hollow interior of said plunger, and a fluid distributing tube detachably secured to said cover plate and forming a continuation of one of said passages whereby circulation of said fluid inside said plunger is improved at the end of said plunger farthest from said cover plate.

6. The improvement of claim 4 in which the plunger is hollow and fluid cooled internally, said plate having an inlet passage and an outlet passage for the cooling fluid and means to supply cooling fluid to said inlet passage, said inlet and outlet passages communicating with the hollow interior of said plunger.

7. In a pump the combination comprising a crosshead, a cylinder, a plunger in cooperative relationship with the crosshead and the cylinder, 50

the crosshead having an opening larger than the cross sectional area of the plunger, a plate blocking passage of said plunger through said opening, and disengageable means securing said plate to said crosshead and said plunger to said plate and said crosshead in said cooperative relationship and disengageable to allow removal of said plate and passage of said plunger through said opening.

10. 8. The improvement of claim 7 in which the plunger is hollow and fluid cooled internally, said plate having an inlet passage and an outlet passage for the cooling fluid, means to supply cooling fluid to said inlet passage, said inlet and outlet passages communicating with the hollow interior of said plunger, and a fluid distributing tube detachably secured to said cover plate and forming a continuation of one of said passages whereby circulation of said fluid inside said plunger is improved at the end of said plunger farthest from said cover plate.

15. 9. The improvement of claim 7 in which the plunger is hollow and fluid cooled internally, said plate having an inlet passage and an outlet passage for the cooling fluid and means to supply cooling fluid to said inlet passage, said inlet and outlet passages communicating with the hollow interior of said plunger.

20. 10. In a pump the combination comprising a crosshead, a cylinder, a plunger in cooperative relationship with the crosshead and the cylinder, a bearing having a bearing surface of limited extent secured to said cylinder, said crosshead having a bearing shoe slidable on said bearing surface between two extreme positions in normal operation of said pump while said cooperative relationship is maintained, the crosshead having an opening larger than the cross sectional area of the plunger, a plate blocking passage of said plunger through said opening, and disengageable means securing said plate to said crosshead and said plunger to said plate and said crosshead in said cooperative relationship and disengageable to allow removal of said plate and passage of said plunger through said opening without separating said shoe from said bearing surface nor moving said crosshead beyond either of said two extreme positions.

ROBERT R. FREUND.
